UNITED STATES PATENT OFFICE

155,349

DESIGN FOR A KNOB

William P. Lear, Brentwood, Calif., assignor to
Lear, Incorporated, Grand Rapids, Mich., a
corporation of Illinois

Application July 21, 1947, Serial No. 140,435

Term of patent 14 years

(Cl. D26—1)

To all whom it may concern:

Be it known that I, William P. Lear, a citizen of the United States, residing at Brentwood, in the county of Contra Costa and State of California, have invented a new, original, and ornamental Design for a Knob, of which the following is a specification, reference being had to the accompanying drawing, forming a part thereof.

Figure 1 is a perspective view of a knob, showing my new design.

Fig. 2 is a side elevational view of the same, and
Fig. 3 is a vertical medial cross section of the
same.

I claim:

The ornamental design for a knob, substantially as shown.

WILLIAM P. LEAR.
